DOOR CLOSING DEVICE

William H. Clewell, Berwick, Pa., assignor to
American Car and Foundry Company, New
York, N. Y., a corporation of New Jersey

Application March 8, 1949, Serial No. 80,187

10 Claims. (Cl. 214—63)

1

This invention relates to door closing devices in general and in particular to such devices intended to be used with mine cars of the drop bottom type having varying length and weight doors.

Mine cars of the drop bottom type ordinarily have the doors interengaging and with the rear-most door held in closed position by a latch. After the cars have been dumped in a bin the doors are hanging vertically and must be closed. Devices for accomplishing this closing have been used but are found unsatisfactory where cars having varying length and weight of doors must operate over the same closing device. In certain large capacity drop bottom cars it has been found necessary to provide doors of varying length and weight in the same car in order to obtain proper load distribution and to avoid necessary car structural obstructions. In the closing of interengaging drop bottom doors each preceding door must be held in a raised position slightly beyond its normal position until the following door has been raised to a position placing a part thereof beneath the preceding door. The door closing devices must be made so that they will lower to permit return of the cars with doors closed over the closing device without contacting the same. It is an object, therefore, of the present invention to provide a door closing device which will raise and lower automatically and will be retained in its fully raised position so long as any doors requiring closing are in contact therewith.

A further object of the invention is the provision of a door closing device having a weight operated portion for locking the device in a raised position.

These and other objects of the invention will be apparent to persons skilled in the art from a study of the following description and accompanying drawings, in which

Fig. 1 is an elevational view of the device with parts in section to better disclose the construction;

Fig. 2 is a plan view of the improved device;

Fig. 3 is an enlarged plan view of a portion of the device;

Fig. 4 is a sectional view taken substantially on line 4—4 of Fig. 3;

Fig. 5 is a sectional view taken substantially on line 5—5 of Fig. 2 but showing the device in fully raised or door closing position; and

Fig. 6 is a partial sectional view showing a slight modification of the device shown in Fig. 1.

Referring now to the drawings in detail it will be seen that the device comprises a base portion

2 A and a ramp portion B which includes a movable or weight-actuated portion C. The base portion A is preferably made of plate welded together to provide a supporting plate 2 adapted to be secured to a supporting structure, such as the framing of the bin into which the mine cars will dump their lading. Vertically extending plates 4 are preferably welded to the base plate 2 and in turn have welded thereto inclined channels having the flanges 6 directed upwardly and the webs 8 forming runways for rollers 10 of the ramp member B.

The rollers 10 support axles 12 extending into downwardly directed sides 14 and stiffening members 16. The side members 14 overlap the sides of the base member A and are guided thereby and at the same time protect the base member with its runways from becoming clogged with lading. A top plate 18 is welded or otherwise secured to the side plates 14 and suitably braced as at 20 against deflection. The rear edges of plates 14 and 18 are curved as at 22, while the forward portion of plates 14 is similarly curved downwardly as at 24. Extension pieces 26 are welded or otherwise secured to the forward lower edges of plates 14 and are connected by a top plate 28, these portions together forming what may be termed a nose portion N, which will be the first portion of the ramp to contact the doors during the closing thereof.

Interposed between the rear edge of plate 28 and the forward edge of plate 18 is a curved weight-actuated plate 30 which forms the door contacting portion of the weight-actuated mechanism C previously referred to. This weight-actuated plate 30 is curved in accordance with and overlaps the forward edge of the side pieces 14 so that when the plate is in its lowered position it will be supported on the edges of the side pieces as clearly shown in Fig. 5. The plate 30 may be suitably braced as at 32 and has welded or otherwise attached thereto arms 34 pivoted as at 36 to the nose portion N. Centrally of the under side of plate 30 lugs 38 are provided on which may be pivotally mounted a link 40, the lower end of which is pivotally connected to the ends of arms 42 of a bell crank member. The bell crank member is pivotally mounted on a shaft 44 supported in brackets 46 welded or otherwise secured to the ramp B. Rigidly attached to the arms 42 is a downwardly extending arm 48 to which may be connected a spring 50 anchored to the side pieces 14 by a cross bar 52. The spring 50 is a tension spring and will constantly tend to hold the plate 30 in the raised position, such as

shown in Fig. 1. Pivotally mounted on shaft 44 between the arms 42 is a pawl 54 having a hooked portion adapted to engage the teeth of a ratchet 56 carried between and non-rotatably secured to the spaced rollers 10 of the forward set of rollers. The pawl 54 is constantly urged toward the ratchet by means of a spring 58 bearing on the pawl and on arms 42. The teeth of the ratchet as plainly shown in Figs. 1, 4 and 5 are so shaped that the ratchet may rotate freely in a counterclockwise direction but will be prevented from rotation in a clockwise direction by the pawl 54 whenever the plate 30 is in the lowered position.

In the form shown in Fig. 6 the tension spring 50 and downwardly extending arm 48 may be eliminated and a compression spring 60 substituted, which spring will be interposed between plate 30 and a pocket formed by bracing members 62 welded or otherwise secured to the forward portion of side pieces 14.

In operation it will be seen that whenever a hanging door of a car such as shown in Pancake Patent 2,374,155 and moving in the direction of the arrow M of Fig. 1 strikes the nose portion N, the entire ramp member B will be moved to the left causing rollers 10 to roll up along the inclined runways 8 to the position shown in Fig. 5. As the car movement continues and during the raising of the ramp member, the door D will wipe along the nose portion and along plate 30 depressing the same to the full line position of Fig. 5 and through spring 58 forcing the pawl 54 into engagement with the teeth of ratchet 56. In so long as any portion of the doors rests upon the plate 30, the pawl 54 will be held in position contacting the ratchet teeth and preventing clockwise rotation of the rollers, thereby preventing return of the ramp to its lowered position. Since the doors of the car interengage in their closed position, the second door will have contacted the nose portion before the first door has slid off of the plate 30, accordingly the ramp will be held in its raised position until all doors of the car have been fully closed. As soon as the last door has been raised and has moved off of plate 30, this plate will return to its raised position due to either tension spring 50 or compression spring 60 and the ramp is then free to move toward the right and into its lowered position. In cases where the open doors of the car are swinging and the speed of the car is such that the doors do not strike the nose portion N prior to contacting plate 30, the ramp can still be moved to the raised position since the pawl 54 will permit counterclockwise rotation of the ratchet 56 through the yielding action of spring 58. Due to the positive locking of the ramp in its raised position a steeper incline on runways 8 may be used than heretofore possible, accordingly a greater lift of the ramp can be obtained without danger of the ramp failing to function through falling to a lowered position when its lowering component exceeds the horizontal component obtained by friction between the sliding door and ramp top.

While the closing device has been described more or less in detail with specific reference to the drawings, it will be obvious that various modifications and rearrangements of parts other than those shown and described may be made without departing from the scope of the invention as defined by the following claims.

What is claimed is:

1. In a door closing device, upwardly inclined runways, rollers supported on said runways for

rolling movement therealong, a ramp supported by said rollers and movable therewith from a lowered to a raised position by doors dragging along the top surface of the ramp, means normally projecting above the top surface of the ramp, and locking means connected to and operated by said projecting means to lock said rollers and ramp in raised door closing position when a door is bearing on said projecting means.

10 2. In a door closing device, upwardly inclined runways, rollers supported on said runways for rolling movement therealong, a ramp supported by said rollers and movable therewith from a lowered to a raised position by doors dragging along 15 the top surface of the ramp, a portion of the top surface of said ramp being resiliently urged upwardly above the adjacent top surfaces of the ramp, and means connected to said portion and operated thereby to lock said ramp in a raised door closing position by the weight of a door resting on said portion.

20 3. In a door closing device, upwardly inclined runways, rollers supported on said runways for rolling movement therealong, a ramp supported by said rollers and movable therewith from a lowered to a raised position by doors dragging along 25 the top surface of the ramp, projecting means normally projecting above the top surface of the ramp, and locking means connected to and operated by said projecting means to lock said rollers and ramp in raised door closing position when a door is bearing on said projecting means, said locking means including a ratchet and pawl device.

30 4. In a door closing device, upwardly inclined runways, rollers supported on said runways for rolling movement therealong, a ramp supported by said rollers and movable therewith from a lowered to a raised position by doors dragging along 40 the top surface of the ramp, a plate member carried by said ramp and normally projecting above the adjacent top surfaces of the ramp, a ratchet wheel secured to one of said rollers, a pawl carried by said ramp and normally out of engagement with said ratchet, and linkage connected to said plate member and operatively connected to said pawl to urge the same into engagement with said ratchet upon downward movement of said plate member relative to said ramp top surface.

50 5. In a door closing device, upwardly inclined runways, antifriction devices supported on said runways for movement therealong, a ramp member supported by said antifriction devices and movable therewith from a lowered to a raised door closing position, and means carried by the forward portion of said ramp member and operable by the weight of a door to lock said ramp member in raised position.

60 6. In a door closing device, upwardly inclined runways, antifriction devices supported on said runways for movement therealong, a ramp member supported by said antifriction devices and movable therewith from a lowered to a raised door closing position, and means carried by the forward portion of said ramp member and operable by the weight of a door to lock said ramp member in raised position, said means including a plate portion resiliently urged upwardly with respect to the remainder of the ramp member.

70 7. In a door closing device, upwardly inclined runways, antifriction devices supported on said runways for movement therealong, a ramp member supported by said antifriction devices and movable therewith from a lowered to a raised

75

door closing position, and means carried by the forward portion of said ramp member and operable by the weight of a door to lock said ramp member in raised position, said means including a pawl and ratchet device preventing rotation of the antifriction devices when in locked position.

8. In a door closing device, upwardly inclined runways, antifriction devices supported on said runways for movement therealong, a ramp member supported by said antifriction devices and movable therewith from a lowered to a raised door closing position, and means carried by the forward portion of said ramp member and operable by the weight of a door to lock said ramp member in raised position, said means comprising a plate portion resiliently urged upwardly with respect to the remainder of the ramp member and connected to a pawl and ratchet device preventing rotation of the antifriction devices when said plate portion is forced downwardly relative to the remainder of the ramp member.

9. In a device for closing a car door, a base member having an upwardly inclined runway secured thereto, a roller supported on said inclined

runway for rolling movement therealong, a ramp including a top plate, said ramp being supported on said roller and movable therewith from a lowered to a raised position by a door dragging along the top plate of the ramp, said top plate including a movable section adapted for movement from the plane of the top of the adjacent plate to a position above the top surface of the plate, means normally urging said movable section to its upper position, and a member supported by the ramp structure and movable by depression of said movable top plate section for locking association with said roller.

10. The structure of claim 9 characterized in that the top plate of the ramp includes a downturned end portion, and the movable section of the top plate is formed in the downturned portion of the plate.
